UNITED STATES PATENT OFFICE

WALTER LINES, OF LONDON, ENGLAND

FOLDING PERAMBULATOR AND THE LIKE

Application filed October 10, 1928, Serial No. 311,688, and in Great Britain November 30, 1927.

This invention relates to folding perambulators, baby carriages and the like and has for its object to provide an improved construction of collapsible framing which is simple to make and use and collapse under a single movement of the handle.

A further object is so to construct the framing as to simplify the attachment of the upholstery and hood fittings and readily to permit a "well" type body to be incorporated in the carriage.

According to the invention the side framings of the body both comprise an upper and a lower horizontal rail united by scissor arms. The pins of the forward ends of the scissor arms however work in elongated slots running horizontally in the rails. The handle arms are separately pivoted to the lower rails at points behind the fixed pivots of the scissor arms, and they are connected by long links articulated at a comparatively small distance above the lower rail to the forwardly and downwardly extending arms of the scissors.

The novelty of the invention lies in the above construction and in the novel combinations and arrangements embodied therein or in the preferred form which it is proposed to describe. These combinations are specifically set out in the claims and are therefore not here specified at length.

The preferred form is illustrated by the accompanying drawings wherein:—

Fig. 1 is an elevation of a perambulator in its open or operative condition,

Fig. 2 shows the same partially, and

Fig. 3 completely collapsed.

Fig. 4 is a half plan view corresponding to Fig. 1.

As shown a lower frame is suitably sprung from the wheels 1, 1 and includes horizontal rails 2 and a fixed wooden structure including seat portions at 3, 3 and a well 4. An upper frame includes horizontal rails 5. A collapsible fabric body 6 is supported by the upper and lower frames. A scissors mechanism in the particular instance shown comprises two links 7, 8 only, these being pivotally connected together at 9 and to the frames at 10, 11. It will, however, be apparent that a multiple-link scissors mechanism (or lazy-tongs)

might in some circumstances be substituted. The forward ends of the links 7, 8 have pins adapted to slide in slots 12, 13 formed in or (as shown) in pieces attached to the rails. Handle arms 14 are pivoted at 15 and are connected to the links 8 by means of long links 16 pivoted at 17 and 18.

It will be appreciated that with such a construction the upper rail moves vertically downwards on the horizontal lower rail in collapsing the frame, and that during this movement all points in the scissor arms except the rear pivots move forwardly an increasing distance as they approach the forward ends of the arms; thus, the forward joint of the long link moves forwardly almost as far as the sliding pivot of the corresponding arms, and it will be appreciated that by pushing the handle forwardly so as to collapse the arms in the forward direction on the bottom rail, the whole of both framings will be collapsed to lie flat.

The upper horizontal rail 5 is not directly connected to the handle arms but is indirectly connected thereto through the provision of a locking stay made up of two sections 19 and 19^a. These sections connected respectively to the upper rail and to the handle arm are also connected for relative movement at their meeting ends, the section 19 being connected to the upper rail preferably at the upper rear pivot of the scissor arm 8, while the section 19^a is pivotally connected to the handle 20. This stay forms a kind of toggle with the adjacent arm 8 of the scissors so as to lie in line with said arm but past dead-centre position when the frames are erected. To collapse the frames in these circumstances it is necessary to flex the joint between the link section 19 and the arm 8, whereupon the handle can then be pushed forward and the frames collapsed. The joint formed at 21 in the stay provides both the pivot and the abutment of a second toggle device and the breaking of this joint from the position of Fig. 1 towards that of Fig. 2 makes a ready means for releasing the main toggle between the stay and arm 8 at the pivot point 11. The connection between the meeting ends of the sections 19 and 19^a is in the form of an abut-

ment 21, of approximately triangular shape, with the base portion fixed to section 19 and the apex pivoted to section 19^a. Then when extended, the edge of section 19 serves to limit the relative movement of the stay in one direction by providing an abutment for the edge of section 19^a, as will be plain from Fig. 1.

It is to be understood that the drawings are illustrative rather than restrictive and are not intended to be interpreted to limit the scope of the appended claims to the construction shown in detail; on the other hand, modifications and equivalents within the spirit of the invention and the scope of the claims when properly interpreted in the light of the prior art are intended to be included therein.

I claim:

- 20 1. A collapsible vehicle including a collapsible body, spaced relatively movable body frames to which the body is secured and through which the body is collapsed and extended, a scissor mechanism between and connected to said frames, a handle for the vehicle pivotally connected to one of said frames, an operating link between the handle and one of the levers of the scissor mechanism, and a locking stay between the handle and one of said body frames.
- 25 2. A collapsible vehicle comprising a collapsible body carried between two body-frame members movable in parallel relationship, a scissor mechanism interposed between the two frames, a folding propelling handle pivoted to the propelling end of the lower frame-member, pull-and-push operating links interposed between the handle and the scissor mechanism and adapted to transmit movement for expanding and collapsing the said mechanism, and locking stays interposed between the upper frame and the handle.
- 30 3. A collapsible vehicle comprising a collapsible body carried between two frame members movable in parallel relationship, a scissor mechanism interposed between the two frames, the forward ends of each member of the said scissors mechanism having a sliding interconnection with the respective upper and lower frame members, a folding handle pivoted to the lower frame member, pull-and-push operating links interposed between the handle and the scissors mechanism, and folding butt-hinged locking stays interposed between the upper frame and the handle.

In testimony whereof I affix my signature.

WALTER LINES.
